(57) **CLAIM**

I claim the ornamental design for the end cap for an air filter, as shown and described.

DESCRIPTION

FIG. 1 is a top perspective view of the top end cap for an air filter embodying our new design.

FIG. 2 is another top perspective view of the top end cap of FIG. 1, as viewed from a different perspective;
FIG. 3 is a bottom perspective view of the top end cap shown in FIG. 1;

FIG. 4 is another bottom perspective view of the top end cap of FIG. 3, as viewed from a different perspective;

FIG. 5 is a top view of the top end cap of FIG. 1;

FIG. 6 is a bottom view of the top end cap of FIG. 1;

FIG. 7 is a front side view of the top end cap of FIG. 1;

FIG. 8 is a rear side view of the top end cap of FIG. 1;

FIG. 9 is right side view of the top end cap of FIG. 1; and,

FIG. 10 is a left side view of the top end cap of FIG. 1.
